UNITED STATES PATENT OFFICE.

JAMES JESSEN, OF MINNEAPOLIS, MINNESOTA, ASSIGNOR TO D. & D. BUTTON-HOLE MACHINE COMPANY, OF MINNEAPOLIS, MINNESOTA, A CORPORATION OF MINNESOTA.

BUTTONHOLE ATTACHMENT FOR SEWING-MACHINES.

1,116,072.

Specification of Letters Patent.

Patented Nov. 3, 1914.

Application filed November 28, 1911. Serial No. 682,948.

To all whom it may concern:

Be it known that I, JAMES JESSEN, a citizen of the United States, of Minneapolis, Hennepin county, Minnesota, have invented certain new and useful Improvements in Buttonhole Attachments for Sewing-Machines, of which the following is a specification.

The object of my invention is to provide a button-hole attachment similar in design 10 to the device shown and described in Letters Patent of the United States, No. 993,070, issued to me May 23, 1911.

A further object is to improve the construction of the attachment shown and described in said patent to the end that the mechanism will be more easily manufactured and more durable and efficient for the purpose designed.

To this end my invention consists in 20 adapting the driving means with respect to the driven coöperating means so that it will automatically adapt itself to different needle bar strokes and provide for the attachment of the device to any style of sewing machine.

25 Further the invention consists in various constructions and combinations, all as hereinafter described and particularly pointed out in the claims.

In the accompanying drawings forming 30 part of this specification, Figure 1 is a bottom view of a button-hole machine embodying my invention, Fig. 1^a is an edge view of the device for determining the proper length of the button-hole, Fig. 2 is a sectional view on the line α — α of Fig. 1, Fig. 3 is a sectional view on the line y — y of Fig. 1, Fig. 4 is a bottom view with the clamp plates removed, Fig. 5 is a detail view of the clamp and shifter plates, Fig. 6 is a detail sectional view showing the means for putting the goods under tension in the clamp plates, Fig. 7 is a vertical sectional view on the line z — z of Fig. 2, Fig. 8 is a front view of the reciprocating plate through which 40 the mechanism is driven, Fig. 9 is a vertical sectional view on the line b — b of Fig. 8, Fig. 10 is a vertical sectional view on the line a — a of Fig. 4, Fig. 11 is an end view, looking toward the clamp plates, Fig. 12 45 is a detail sectional view showing the improved means for oscillating the clamp plates to form the bight of the stitches, Fig. 13 is a bottom view with the clamp, feed and shifter plates removed, showing the 50 means for increasing or decreasing the bight 55

of the stitches, Fig. 14 is a detail view of the trip mechanism or the improved means for reversing the feed screw, Fig. 15 is a detail bottom view, illustrating the feeder plate guides, Fig. 15^a is a sectional view on the line N—N of Fig. 15, Fig. 16 shows a modified form of drive connection to the needle bar pin.

In the drawings, 2 represents the base or frame, in which a portion of the operating mechanism is mounted. A bracket 3 is mounted integrally on this base and has bearings for a rock shaft 4. One end of this rock shaft is provided with an arm 5 that is adapted to engage a vibrating needle bar, (not shown). The rock shaft is arranged in a substantially horizontal position and at the opposite end from the arm 5 is provided with a rocker 6 arranged in a vertical plane and having a rocking movement with the 60 operation of the needle bar. A stationary plate 7 is interposed between the rocker 6 and the end face of the bracket 3 and on the other side of the rocker is a plate 8 having a series of lugs 9. These lugs project horizontally into the path of the rocker 6 so that when the rocker is operated the plate 8 will be moved to describe a rectangular path, substantially as shown and described in my 65 patent above referred to. The plate 8 also has a lug 12 which projects into a recess 13 formed in the plate 7, the outline of this recess correspondingly substantially to the path described by the plate 8 in the operation of the rocker, and in the center of this 70 recess a pin 14 is provided, which prevents the lug 12 from becoming centered in the recess and the plate 8 from becoming centered with respect to the rocker. (See Fig. 7). This recess and pin are provided merely 75 as a safeguard and do not affect the movement of the reciprocating plate.

As indicated in Fig. 7, the arms of the rocker do not contact squarely the full length of the stroke with the faces of the lugs or the plate 8, but are positioned to slide by the edges of the lugs at the end of the movement of the plate 8, in case the stroke of the needle bar is longer than what would be sufficient to move the plate the full distance and thereby adapt the attachment to needle bars of different stroke. This arrangement permits the attachment of the device to any style of sewing machine and machines varying in the length of the stroke of the needle bars.

2 A plate 15 is mounted on the plate 8 and has inwardly turned flanges 16 overlapping the plate 8 and vertically movable therewith. (See Figs. 7 and 8). A spring 19 is mounted on the cover 11 and exerts a yielding pressure on the plate 15 and a plate 20 is interposed between the cover 11 and the plate 15 and has diagonal slots 21 therein to receive correspondingly arranged lugs 22 formed in the plate 15.

10 The sides of the stationary plate 7, (see Figs. 8, 9 and 12) project outwardly and are cut away to form slots 24 and 25, and the plate 15 is provided with shoulders 17 projecting into the slots 25 which limit the vertical movement of the plate 15 while the side flanges 7' guide it horizontally.

15 The plate 20 is provided with a flange 20' that projects into and is guided in the slots 24. A horizontal extension of this flange 20' carries a downwardly projecting lug or pin 26.

20 The lower end of the plate 8 has a series, preferably three, of horizontally projecting lugs 27 which are adapted to extend between the pins 28 of a feed wheel 29 having a hub 30 that is mounted on a shaft 31. This feed wheel and the lugs engaging the teeth or pins of the wheel are substantially the same 25 as the ones shown and described in my patent above referred to, the lugs passing from one side of the feed wheel to the other, one lug moving from its position between the teeth on one side to an inoperative position 30 and setting the other lug in an operative position between the teeth on the other side. This feature of the device, being fully illustrated and described in my former patent, needs no detailed description herein.

35 40 The hub 30 is secured to the shaft 31 by means of a pin 32, (see Fig. 2). The head of this pin is adapted to slide in a slot 33 provided in a screw 34 that is mounted on the shaft 31 between a plate 35 and a tongue 36 that is pressed or punched out of the plate 35. The plate 35 has a pivotal connection at 37 with the bracket 3 and the tongue 36 is upwardly turned and has one end projecting into a slot 38 in the plate 7, said slot being 45 of sufficient length to allow a limited lateral movement of the tongue 36 therein. This tongue 36 has a bearing for the hub 30 and the shaft 31 and moves back and forth in its slot in the plate 7 to allow the shifting of 50 the feed wheel for the purpose of changing the direction of revolution of the screw. The hub 30 has a limited sliding movement in its bearing in the plate 36 and the shaft 31 also has a limited longitudinal movement 55 in the screw 34, the slot 33 being of sufficient length to permit said movement against the tension of a spring 39 that is mounted on the shaft 31. This shaft has an extension 40 provided with a finger grip 41. The purpose 60 of this construction is to allow the operator 65

to grasp the part 41, pull the shaft 31 outwardly and disengage the pins or teeth of the feed wheel from the lugs of the actuating plate. When the teeth of the feed wheel have been disengaged from the actuating plate the mechanism can be set to overlap the stitches and thereby avoid the gap at the point between the beginning and end of the stitches. It also allows of returning the clamp plates at any point of the button-hole 70 to overlap the stitches in case a thread breaks. As soon as the finger grip 41 is released the spring 39 will return the parts to their normal position. (See Fig. 2.)

75 42 represents the upper clamp plate and 80 43 the lower clamp plate. (See Figs. 3 and 6). The lower clamp plate has bars 42' with a space between them adapted to receive depending flanges 43' on the upper clamp plate, said bars having outer beveled 85 faces 42'' between which and the flanged edge 43'' of the upper clamp plate the material is gripped simultaneously therewith. The flanges 43' press on the material between the bars 42' and hold it firmly on the 90 work plate 44', drawing the goods over the bars 42' and applying tension thereto. (See Fig. 6.) A plate 44 has a forked end that is loosely connected at 45 to the upper clamp plate, said loose connection allowing the 95 upper clamp plate to set itself squarely on the lower plate and the work plate. The plate 44 is guided by a bracket 46 which projects upwardly from the lower clamp plate and is provided with a compression 100 spring 47 and a cam lever 48, by means of which the forked end of the plate 44 and the upper clamp plate can be forced downwardly to grip the goods. (See Fig. 3.) The work plate, which forms a continuation 105 of the base plate of the attachment, has a roller 49 mounted in its upper surface, parallel and contacting with the under surface of the clamp plate 43. A similar roller 50 is mounted in the carrier 51 in the base of 110 the attachment and is held with a yielding pressure against the lower clamp plate by means of a spring 52, said carrier having a pin 53 that is slidable in the base plate 2 and guided in the plate 54. These rollers 115 provide an anti-friction surface for the free transverse movement of the clamp plates, but resist their longitudinal movement, a function of the clamp plates incidental to the formation of the bars at the ends of the 120 button-hole and the width of the button-hole, as will hereinafter appear.

125 A plate 55 is adapted to fit against the underside of the base and has slots 56 and 57 therein to receive pins 58 and 59 depending from said base, and said base has a slot 60 in which a screw 61, mounted on said plate 55, is slidable, said screw having a thumb nut 62. Upon loosening this thumb nut the plate 55 may be moved lengthwise 130

on the pins 58 and 59. (See Figs. 3 and 13.) The forward end of the plate 55 is provided with depending lugs 63 having curved faces 64. These lugs are adapted to enter a slot 65 in a shifter plate 65', the curved faces of said lugs bearing on the walls of the plate inclosing said opening and forming pivots on which the shifter plate and the upper and lower clamp plates 55 and 65' oscillate horizontally. (See Fig. 4.) The longitudinal adjustment of the plate 55 will obviously change the position of the pivot of the shifter and clamp plates and regulate the throw or travel of the material held between the clamping faces of said plates. Thus the bight or length of the stitches may be regulated. The lugs 63 are pressed out of the plate 55, (see Fig. 13) and form a substantial bearing for the shifter plate to oscillate upon. The curved faces of these lugs form broad, substantial bearings and positively define the stroke of the parts within certain predetermined limits. Often in attachments of this kind considerable trouble is experienced, owing to the variation in the movement of the parts, due to momentum or difference in speed. I have not only avoided this objection by providing bearings of this kind, but also cheapen the construction. The shifter plate also has a longitudinal slot 66 therein, (see Fig. 4) to receive the slightly curved head on the pin 26, so that when the plate 20 is reciprocated, the engagement of the pin 26 with the shifter plate will oscillate the clamp plates and the work to form the bight of the stitches. This pin 26 has curved bearing faces thereon which operate to positively limit the oscillation of the shifter plate thereon and prevent any variation in the movement of the parts due to momentum or speed. I regard this form of bearing for the vibrating plates as an important feature of my invention.

Between the shifter plate and the plate 55 I interpose a feed plate 67, having longitudinal slots 68 and 69 therein to receive the projecting ends of the pin 58 and shoulders 59 provided on plate 54, said feed plate being slidable thereon. (See Figs. 4 and 15.) This feed plate has a lug 70 to enter a slot 71 in the shifter plate, said lug operating to feed the shifter plate forward and backward. The feed plate has laterally extending, horizontal arms 72 and 73 connected at their outer ends by a bar 74. (See Fig. 15.) The arm 73 has a depending finger 75 which engages the threads of the screw 34 so that with the revolution of the screw the feed plate will be caused to operate the clamp plates. (See Figs. 2 and 4.) The plate 35 has a horizontal extension 76 on which slides 77 and 78 are mounted, being held apart by the tension of a spring 79. (See Fig. 14.) These slides have beveled ends 80 and 81.

A pin 82 depends from the base of the machine and engages the beveled end of the outer plate 80 and a trip lever 83 is pivoted at 84 and has a shoulder 85 in position to engage the beveled surface 81. (See Fig. 14.)

Upwardly projecting lugs 86 and 87 are provided on the trip lever 83, extending into the path of the depending lugs 23. (See Figs. 7 and 14). The engagement of the lug 23 with the lug 86 will oscillate the plate 35 and the screw carried thereby to shift it and the feed wheel and reverse the direction of movement of the screw. When this shifting takes place the slide 77 will be pushed inwardly, the beveled surface 80 passing from one side of the pin 82 to the opposite side, the pressure of the slide on the pin normally holding the screw against premature movement. The lugs 86 and 87, being carried by the oscillating lever 83, will evidently be in the path of the actuating lugs 23 alternately, so that when one of the depending lugs 23 engages an upwardly projecting lug of the trip lever 83, the other lug of the trip lever 83 will be out of the path of the lug 23. This shifting of the lever 83 must take place at the end of the button-hole, and one movement is effected by the arm 72 engaging a depending lug 88 on the trip lever 83 when the finger 75 has reached one end of the feed screw. The parts will then assume the position indicated by dotted lines in Fig. 14, or by full lines in Fig. 1.

To shift the lever 83 back to the position indicated by full lines in Fig. 14 at the opposite end of the button-hole, I provide an arm 89 having guide lugs 89' projecting horizontally beneath the feed plate and adjustable by means of a thumb screw 90 in a slot 91 in said feed plate. The position of this arm in the slot determines the length of the button-hole, for as soon as the feed plate reaches a point where the arm will engage the lug 88 of the trip lever, the lever will be thrown to the position indicated by full lines in Fig. 14 and the plate supporting the feed screw will be oscillated to reverse the direction of movement of the feed wheel. The feed plate 67 is provided with a lug 89'' and by inserting a button 89''' against this lug the operator of the machine can determine the proper length of the button-hole for this particular button. (See Figs. 1 and 4).

Referring to Fig. 5, I have shown a means for allowing movement of the clamp plates at the ends of the button-hole to form the bars and regulate the distance between the sides of the button-hole. This means consists in providing lugs 92 on the shifter plate, projecting downwardly into diagonal slots 93 in the lower clamp plate. A set screw 94 carried by the lower clamp plate engages the edge of the shifter plate and regulates the movement of the clamp plate on the lugs 92.

At the end of the button-hole, when the shifter plate is reversed, the lugs of the said plate will return in the diagonal slots and force the clamp plate in a transverse direction the desired distance, or until the shifter plate strikes the screw 94. This transverse movement of the clamp plate forms the bar at the end of the button-hole directly at right angles to the sides of the button-hole. The length of this bar will depend upon the adjustment of the screw 94. Obviously, the screw can be set so that the second row of stitches will be made directly upon the first row. If, however, sufficient transverse movement of the clamp plate is permitted, a bar will be formed at the end of the button-hole and the return movement will form a second row of stitches parallel with the first on the opposite side of the button-hole. In this transverse movement of the clamp plate the anti-friction rollers 49 and 50 perform their functions, resisting lengthwise movement of the plate induced by the action of the lugs 92 against the diagonal sides of the slots 93, but allowing it to slide freely, transversely. (See Figs. 3 and 5).

It is desirable in an attachment of this kind to provide means for clamping it to the bed or base of any style of sewing machine. Referring to Fig. 11, 95 represents a sewing machine arm, and 96 a threaded rod having a horizontal extension 97 provided with a serrated upper surface 98 which engages the under surface of the arm 95. The rod 96 fits loosely in a socket 99 provided on the bracket 3, a pin 100 being vertically movable in a slot 101 in said bracket and preventing rotation of the threaded rod therein. A nut 102 is mounted on the threaded rod and adapted to engage the upper walls of the socket and raise the threaded rod until the arm 97 bears firmly on the underside of the arm 95. The heads on the screws 103 which secure the combined base plate and work plate to the attachment base form three-point bearings, resting upon the bed of the sewing machine so that when the nut 102 is tightened sufficiently the attachment will be firmly clamped on the machine, the length of the arm 97 allowing variation in the position of the attachment on the machine bed and the desired angle with respect to the sewing machine arm. The corrugated surface 98 upon the extension 99 of the threaded rod materially aids to secure the attachment firmly to the sewing machine without undue pressure on the parts.

In Fig. 16 I have shown a modified construction designed to prevent to a large degree the sound of the rocker when it contacts with the lugs of the sliding plate. In certain portions of the stroke of the rocker this noise is particularly noticeable and I have found that the construction shown in Fig. 16 eliminates to a considerable extent

this objection. As shown in the figure, 104 is a cam slot provided in an arm 105 that is secured on the rock shaft 4. 106 is a pin mounted on a lever 107 that is pivoted at 108 on the frame of the attachment. This pin slides in the slot 104 and, bearing on the walls thereof, operates to retard the speed or impetus of the rocker at the point of contact with the projecting lugs on the sliding plate, thus deadening the sound without affecting the efficiency of the device.

In the operation of the device, the cloth is clamped between the upper and lower clamp plates. As the needle vibrates, the rock shaft 4 is oscillated and the plate 8 moved in a rectangular path. The plate 15 will be moved up and down through the operation of the plate 8 and will reciprocate the plate 20 longitudinally. The rocker connection between the plate 20 and the shifter plate will cause the oscillation of the shifter plate. The lateral vibration of the clamp plates will position them to form the button-hole stitch. The plate 8 is moved in a rectangular path and in turn will give the feed screw an intermittent rotation. Said feed screw, through its connection with the feed plate, will gradually carry the clamp plates in a longitudinal direction, thereby spacing the stitches along the edge of the button-hole. When the end of the button-hole is reached, the feed screw will be shifted by one of the lugs 23 operating in connection with the lever 83, which has been previously set in the path of one of the lugs by the operation of the arm 72 or the arm 89. The shifting of the feed screw will change the position of the feed wheel so that the lug on the plate 8, which previously was inoperative to engage the teeth on one side of the wheel, now becomes operative to engage the teeth on the other side of the wheel to reverse the direction of movement of the wheel and screw. The lateral movement of the clamp plates on the shifter plate allows for the formation of the bar at the end of the button-hole, the adjustment of the screw 94 regulating the number of the stitches forming the bar. When the bar has been stitched, the reverse movement of the feed screw operating in connection with the other mechanism described forms a second row of stitches, parallel with the first, to complete the button-hole.

I claim as my invention:

1. In a button-hole attachment for sewing machines, the combination, with a clamp plate and a feed plate, of a sliding member and means for actuating said sliding member in a peripheral path, the engagement of said actuating means with said member permitting variation in the stroke of said means to adopt the attachment for sewing machines of varying stroke.

2. In a button-hole attachment for sewing

- machines, the combination, with a clamp plate and a feed plate, of a feed screw operatively connected with said feed plate, an operating plate for said feed screw, means 5 for moving said operating plate in a rectangular path, the engagement of said means with said plate allowing variation in the stroke of said means to adapt the attachment for sewing machines of varying stroke, 10 and means carried by said plate for engaging and intermittently rotating said feed screw.
3. In a button-hole attachment for sewing machines, the combination, with a clamp plate and a feed plate, of a rock shaft, a rocker secured on said shaft and having arms projecting therefrom, a sliding plate having means in the path of said arms and moving in the outline of a rectangle, said 15 arms during the latter part of their stroke being adapted to pass by said means, whereby variation in the stroke of said rocker is permitted, a guide for said sliding plate, and a feed screw operated by said sliding plate 20 and connected with said feed plate.
4. In a button-hole attachment for sewing machines, the combination, with a clamp plate and a feed plate, of a sliding member and means for actuating said sliding member in a circumscribed rectangular path, means operating to prevent the centering of said sliding member with respect to said 25 actuating means.
5. In a button-hole attachment for sewing machines, the combination, with a clamp plate and a feed plate, of a stationary plate having a recess therein and a fixed pin centrally arranged in said recess, a sliding plate and means for actuating it in a circumscribed rectangular path, the outline of said 30 recess conforming to the path described by said sliding plate, said sliding plate having a lug projecting into said recess whereby the centering of said sliding plate with respect 35 to said actuating means will be prevented, a feed screw, means for intermittently rotating said feed screw, and means actuating said feed plate from said feed screw.
6. The combination, with a feed plate 40 and a clamp plate, of a feed screw, means operatively connecting said screw with said feed plate, a feed wheel having means for connection with said feed screw, means for operating said feed wheel to revolve said screw, means for normally holding said feed 45 wheel in engagement with said operating means, and means for temporarily withdrawing said feed wheel from engagement with said operating means.
- 60 7. The combination, with a clamp plate and a feed plate, of a feed wheel operatively connected with said feed plate, a member provided with a tooth on each side of the center of said wheel and having alternate setting and working strokes, said teeth mov- 50 ing alternately during the setting strokes into working position upon opposite sides of the center of said wheel to engage and revolve it in one direction during the working strokes, means for actuating said member, and means for temporarily separating said teeth and wheel to permit the re-setting of said clamp plate at any point on the button-hole.
8. The combination, with a clamp plate 75 and a feed plate, of a feed wheel operatively connected with said feed plate, means movable in an indirect path and having teeth upon opposite sides of the center of said wheel, said teeth engaging said wheel alternately to impart an intermittent revolving movement thereto, a tooth on one side of the center of said wheel being in position to engage and operate said wheel while a corresponding tooth on the other side of the center of said wheel is in an inoperative 80 position, means for imparting a continuous movement to said movable means, means for shifting said feed wheel with respect to the teeth of said movable means to reverse 85 the position of their engagement therewith and thereby reverse the direction of movement of said wheel, and means for temporarily disconnecting said feed wheel from said movable means to permit the resetting 90 of said clamp plate at any point on the button-hole.
9. The combination, with a feed plate and a clamp plate, of a feed screw, means operatively connecting said screw with said feed plate, a feed wheel having a sliding connection with said feed screw, means for operating said feed wheel to revolve said screw, a spring normally holding said feed 100 wheel in engagement with said operating means, and means for temporarily withdrawing said feed wheel from engagement with said operating means against the tension of said spring.
10. The combination, with a clamp plate 105 and a feed plate, of a feed screw, means operatively connecting said feed screw with said feed plate, a shaft fitting within said screw, a feed wheel secured on said shaft and having a sliding connection with said screw, said sliding connection allowing the independent sliding movement of said feed wheel but causing the simultaneous rotation of said feed wheel and said screw, means 110 for actuating said feed wheel to operate said screw, said shaft having a finger grip and being capable of longitudinal movement with said feed wheel to retract said wheel out of engagement with said operating means.
11. The combination, with a clamp plate 115 and a feed plate, of a feed screw, means operatively connecting said feed screw with said feed plate, a shaft slidable lengthwise in said feed screw, a feed wheel mounted 120

on said shaft and having means projecting into a slot in said screw, whereby said wheel and screw will revolve simultaneously and said wheel will have a sliding movement 5 with said shaft independently of said screw, means for actuating said wheel to revolve said screw, the longitudinal movement of said shaft allowing said wheel to be retracted from said actuating means, and a 10 spring normally holding said wheel in engagement with said actuating means.

12. In a button-hole machine, the combination, with a clamp plate and a feed plate, of a sliding member and means for actuating 15 said sliding member in a peripheral path, said sliding member completing its cycle during every two reciprocations of the needle, a feed screw operatively connected with said feed plate for actuating 20 said clamp plate, means for operating said feed screw from said sliding member, and means for temporarily withdrawing said feed screw from operative connection with 25 said sliding member, for the purpose specified.

13. The combination, with a plate having lugs thereon provided with comparatively long bearing surfaces, of a shifter plate arranged to oscillate on said bearing surfaces, a vibrating clamp plate carried by said shifter plate, said bearing surfaces having 30 end portions operating as stops to limit the degree of oscillation of said shifter plate and prevent overthrow of said vibrating clamp plate.

14. The combination, with a base, of a plate slidably mounted thereon, lugs carried by said plate and having curved bearing surfaces, an oscillating plate having an 40 opening to receive said lugs, the walls of said opening bearing on the curved surfaces of said lugs and rocking thereon, a vibrating clamp plate carried by said shifter plate, the edges of said lugs limiting the 45 stroke of said shifter plate and preventing over vibration of said clamp plate.

15. The combination, with a vibrating clamp plate and an oscillating shifter plate having a longitudinal slot therein, of a sliding plate having lugs formed thereon, and means for operating said sliding plate, a reciprocating plate having slots to receive 50 said lugs and actuated thereby, a pin carried by said reciprocating plate, said pin being adapted to enter the slot in said shifter plate and provided with bearing faces, the 55 end portions of said faces operating to prevent the overthrow of said clamp plate and the consequent variation in its vibration.

16. The combination, with a base, of a plate slidably mounted thereon and having lugs pressed or punched therefrom, said 60 lugs having bearing surfaces, a shifter plate having a bearing on said lugs and guided thereby, a clamp plate vibrated by said

shifter plate, the surfaces of said lugs allowing the oscillation of said shifter plate thereon but preventing the overthrow of said clamp plate and means for operating 70 said shifter plate.

17. The combination, with a base, of a feed plate and means for actuating the same, lugs having curved bearing surfaces, a shifter plate, said feed plate and said shifter plate having openings therein to receive said 75 lugs, said shifter plate oscillating on the curved surfaces of said lugs and forming the bight of the stitches, means for operating said shifter plate and a clamp plate connected with said shifter plate. 80

18. The combination, with a clamp plate and a feed plate, of a feed screw, a pivoted plate wherein said feed screw is mounted, means for revolving said feed screw, means for operating said feed plate from said 85 screw, slides mounted on said pivoted plate and having beveled surfaces, a spring holding said slides apart, a pin in the path of the beveled surface of one of said slides, a trip lever having means to engage the beveled 90 surface of the other slide, means connected with said feed plate for operating said trip lever, and means for oscillating said pivoted plate to change the direction of revolution 95 of said screw.

19. The combination, with a base and a bracket mounted thereon, of a plate pivoted on said bracket and depending therefrom, a tongue pressed or punched from said plate, means having a slot to receive the end of 100 said tongue and limit the oscillation of said plate, a feed screw having bearings in said plate and in said tongue, means for revolving said screw, a feed plate operatively connected with said screw, a clamp plate, means 105 for normally holding said pivoted plate at the limit of its oscillation in either direction, and means for shifting said plate to change the direction of revolution of said screw.

20. The combination, with a feed plate 110 and an oscillating shifter plate mounted thereon and means for operating said feed plate and shifter plate, of a clamp plate provided with diagonal slots, said shifter plate having lugs to enter said slots, said 115 clamp plate having a limited movement on said lugs, means for limiting the extent of such movement, and anti-friction rollers contacting with said clamp plate and resisting longitudinal movement thereof but facilitating transverse movement of said clamp plate. 120

21. The combination, with a clamp plate, a feed plate, and a shifter plate and means for actuating said feed plate and shifter 125 plate, said shifter plate having lugs adapted to enter diagonal slots in said clamp plate, of anti-friction bearings for said clamp plate, said bearings resisting longitudinal movement of said clamp plate but permit- 130

ting greater freedom of lateral movement, the lugs of said shifter plate allowing a transverse movement of said clamp plate, and means carried by said clamp plate and 5 engaging said shifter plate for regulating the degree of said movement, and thereby the length of the bar at the end of the button-hole.

22. The combination, with a clamp plate 10 and means for vibrating it, of a feeding means comprising a feed screw, a pivoted frame whereon said feed screw is mounted, a trip lever pivoted upon said frame, means for oscillating said trip lever in opposite 15 directions past a dead center, means engaging the said trip lever for shifting the said pivoted frame, and a spring tensioned to move the said trip lever and the said pivoted frame in either direction after having passed 20 the dead center.

23. The combination, with a clamp plate and a feed plate, of a feed screw, means operatively connecting said feed screw with 25 said feed plate, means for operating said feed screw, means for shifting said feed screw to change its direction of revolution, a trip lever controlling the operation of said shifting means, an adjustable arm carried by said feed plate and adapted to engage 30 said trip lever to operate the same, said feed plate having a slot wherein said arm is slideable, the position of said arm in said slot determining the length of the button-hole, and said slot being adapted to receive 35 a button between one end wall thereof and said arm, whereby the length of the button-hole can be proportioned to the size of the button.

24. The combination, with a sewing ma- 40 chine arm, of a button-hole attachment having a base provided with a three-point bearing adapted to rest on the sewing machine table, an upright threaded rod mounted in said base and having means preventing rota- 45 tion therein, means mounted on said rod and engaging said base to raise and lower said rod, said rod having a horizontal arm at its upper end that is adapted to bear on the sewing machine arm, for the purpose 50 specified.

25. The combination, with a sewing ma- 40 chine arm, of a button-hole attachment having a base adapted to rest on the sewing ma-

chine table and provided with a vertical socket therein, a threaded rod fitting within 55 said socket and having means preventing rotation therein, a nut mounted on said rod and engaging the walls of said socket to raise and lower said rod when said nut is revolved, said rod having a horizontal arm 60 at its upper end that is adapted to extend under said sewing machine arm and bear thereon, for the purpose specified.

26. The combination, with a clamp plate, 65 of a feed screw, means operatively connect- ing said feed screw with said clamp plate, means for shifting said feed screw to change the direction of revolution, a trip lever controlling the operation of said shifting means, an arm arranged to engage and operate said 70 trip lever, said arm being movable toward and from a fixed wall between which and said arm a button may be inserted, whereby the position of said arm may be determined to trip said lever at a predetermined point 75 and proportion the length of the button-hole to the size of the button.

27. In a button-hole attachment for sewing machines, the combination, with a clamp plate and a feed plate, of a vibrating mem- 80 ber operating in a peripheral path, and means having arms thereon for actuating said member, the engagement of the arms of said actuating means with said member allowing a variation in the stroke of said 85 means, for the purpose specified.

28. In a button-hole attachment for sewing machines, the combination, with a clamp plate and a feed plate, of a feed screw op- 90 eratively connected with said feed plate, an operating member having a peripheral path for said feed screw, means having arms for vibrat- 95 ing said operating member, the engagement of said arms with said member allowing variation in the stroke of said means to adapt the attachment for sewing machines of varying stroke, and means for engaging and intermittently rotating said feed screw.

In witness whereof, I have hereunto set 100 my hand this 23d day of November, 1911.

JAMES JESSEN.
